ELECTRIC LAMP BULB

Roy W. Clough, Chicago, Ill., assignor to Sears, Roebuck and Co., Chicago, Ill., a corporation of New York

Filed Feb. 17, 1969, Ser. No. 15,820

Term of patent 14 years

Int. Cl. D26—01

U.S. Cl. D26—8

FIG. 1 is an elevational view of an electric lamp bulb embodying my new design, and

FIG. 2 is a top plan view of the same.

The characteristic feature of my design resides in the specific configuration of the lamp envelope.

I claim:

The ornamental design for an electric lamp bulb, as shown and described.
